UNITED STATES PATENT OFFICE.

WALTER E. VERCLAIRE, OF CHICAGO, ILLINOIS.

AEROPLANE.

1,093,746.

Specification of Letters Patent. Patented Apr. 21, 1914.

Application filed December 23, 1912. Serial No. 738,201.

To all whom it may concern:

Be it known that I, WALTER E. VERCLAIRE, a citizen of the United States, and a resident of the city of Chicago, county of Cook, 5 and State of Illinois, have invented certain new and useful Improvements in Aeroplanes, of which the following is a specification.

My invention relates to aeroplanes and 10 particularly to mechanism for guiding and stabilizing the same.

The object of this improvement is to provide a simple and effective device whereby 15 the planes in which the propellers rotate will be tilted in accordance with the tilting of the stabilizing planes in order to facilitate the control of the aeroplane.

Other objects will appear hereinafter.

The invention consists in the combinations 20 and arrangements of parts hereinafter described and claimed.

The invention will be best understood by reference to the accompanying drawings forming a part of this specification, and in 25 which,

Figure 1 is a broken longitudinal section of an aeroplane embodying my invention, Fig. 2 is a section of the same taken on line a-a in Fig. 1 and looking in the direction 30 of the arrows 2-2, Fig. 3 is a similar view of the same taken on line a-a of Fig. 1 but looking in the direction of the arrows 3-3, Fig. 4 is an enlarged detail view, in perspective, of the controlling lever and its 35 mounting, Fig. 5 is a rear elevation of the stabilizing and guiding planes, Fig. 6 is an enlarged vertical section taken on line 6-6 in Fig. 1, Fig. 7 is an enlarged section taken on line 7-7 in Fig. 3, and Fig. 8 is an enlarged fragmental section taken on line 8-8 in Fig. 5.

The preferred form of construction, as 45 illustrated in the accompanying drawings, comprises a central beam 9 in the top portion of the aeroplane and extending the full length thereof and a keel 10 connected with the front end of the beam 9 and curved downwardly for a distance, then extending parallel with the beam 9 throughout the 50 length of the aeroplane. A plurality of posts 11 are secured between the beam 9 and keel 10 which with a plurality of tie wires 12 space the beam 9 and keel 10 rigidly apart. Extending laterally from the beam 9 is a

plurality of upwardly curved ribs 13 spaced 55 apart and provided with a rail 14 at their outer ends to space these outer ends apart. Secured to the tops of the ribs 13 is a conventional covering 15 of suitable fabric. A plurality of tie wires 16 connect the keel 60 10 with the rails 14, as is clearly illustrated.

A front wheel 17 is mounted in a suitable fork 18 and the latter is journaled in suitable journals in the keel 10 to support the forward end of the aeroplane when resting on the ground. The fork 18 is provided with laterally extending arms 19 which are connected by means of the cables 20 to the steering mechanism of the aeroplane which will be described later. The rear end of the 70 aeroplane is supported on a pair of rear wheels 21 mounted on a suitable axle 22 which latter is secured to the keel 10. The axle 22 is further secured to the keel by means of brace wires 23 as is fully illus- 75 trated in Figs. 1 and 2.

Mounted in the forward part of the aeroplane immediately over the front wheel 17 is a post 24 which is provided with a slot 25 and secured on the sides of the post 24 80 are angular shaped supports 26 which are provided with perforations registering with a perforation through the central portion of the post 24 to provide suitable bearings for a rotating shaft 27. In the slot 25 on the 85 shaft 27 is secured a lever 28 to rotate with said shaft 27. On the ends of the shaft 27 extending through the brace members 26 are mountings 29 upon which are mounted the motors 30 which furnish power for the propellers 31. The motors 30 may be of any preferred form and construction but the rotary type of engine is preferred. A propeller shaft 32 is mounted in a suitable perforation in the mounting 29 to transmit 90 power from the motors 30 to the propellers 31.

Rotatively mounted in the rear portion of the aeroplane is a perpendicularly disposed post 33 with a slot 34 mounted in suitable 100 bearings in the beam 9 and keel 10. Fitted on a pivot 35 is a lever 36 in the slot 34 of the post 33 for vertical swinging. A handle portion 37 is provided on the end of lever 36 and extended to a convenient position near the operator's seat 38 in the aeroplane.

Secured near the tops of the vertical post

33 and post 24 are pulleys 39 over which cables 40 are passed. The end portions of the cables 40 are connected to suitable positions on levers 36 and 28 to effect simultaneous pivotal movement of said levers.

The vertical post 33 extends through the keel 10 and is provided on its bottom end with a lever 41 and said lever 41 is operatively connected with the arms 19 of the fork 18 to effect guiding of the aeroplane when the same is on the ground. A vertical post 42 is journaled in the rear end portions of the beam 9 and keel 10 and is provided with a longitudinally extending slot 10 in which is secured the rudder plane 43. Near the lower end of said post 42 are laterally extending arms 44 which are connected, by means of cables 45, to arms 46 formed on the lower end of the vertical post 33 to 15 cause the shaft 42 to rotate simultaneously with the shaft 33 to effect guiding of the aeroplane. 20

25 Stabilizing planes 47 are mounted on a suitable slotted shaft 48 which is journaled in a bearing through the post 42 and rudder plane 43 as is clearly shown in Figs. 7 and 8. The construction is such, that the stabilizing planes 47 will turn with the shaft 48, as indicated by the dotted lines in Fig. 1.

30 Pulleys 49 are mounted near the top and bottom portions of the post 42 and on the beam 9 and near the bottom of one of the posts 11, as clearly illustrated in Fig. 1. Cables 50 are secured to the rear ends of the stabilizing planes 47 and passed over the pulleys 49 and connected with the lever 36 to effect tilting of the stabilizing planes 47 upon pivotal movement of the lever 36 on its pivotal point 45.

40 In operation, the aeroplane is placed in a suitable position to make flight and the engine started in the usual manner. The operator moves lever 36 on its pivotal point 35 in the direction indicated by dotted lines 36' 45 in Fig. 1 to effect tilting of the propellers 31 in the direction indicated by the dotted lines 31' in the same figure and the stabilizing planes 47 in the direction of the dotted lines shown in the same figure to effect 50 a cent of the aeroplane. It will be seen that when the propellers are inclined in the direction indicated they will exert an upward as well as a forward pull on the aeroplane and as soon as the aeroplane begins to 55 lift the tilting of the stabilizing planes 47, as indicated, will increase the angle of incidence of the lifting planes which comprises the ribs 13, covering 15 and connecting portions. In this manner ascension may be 60 made more quickly than with aeroplanes of conventional type. When it is desired to descend the lever 36 is moved in the opposite direction than that indicated to effect 65 tilting of the propellers 31 and the stabilizing planes 47 in opposite directions than

those indicated to cause the machine to descend more quickly.

The bottom of post 33 being connected with the post 42 for simultaneous rotation, it will be seen that upon laterally swinging 70 of the lever 36 on the journals of the post 33 corresponding movement of the rudder plane 43 will be effected to guide the plane. When the machine is on the ground, similar lateral movement of the lever 36 on the journals of the shaft 33 will effect steering the 75 aeroplane by means of its connection with the front wheel 17 as has already been explained.

While I have illustrated and described the preferred form of construction for carrying my invention into effect this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. In an aeroplane, the combination of a frame; a propeller pivotally mounted in said frame; a post in said frame; a vertically movable lever pivoted on said post; a second vertical post in said frame; a stabilizing plane pivoted for vertical movement on said last mentioned post; and cables operatively connecting said propeller and stabilizing plane with said lever, substantially as described. 100

2. In an aeroplane, the combination of a frame; a propeller mounting in said frame; a lever on said mounting; a controller lever pivoted on said frame; a cable connecting the forward end of said lever with the rearward end of said controller lever; a cable connecting the rearward end of said lever with the forward end of said controller lever; a stabilizing plane pivotally mounted in said frame; and cables operatively connecting said controller lever with said stabilizing plane, substantially as described.

3. In an aeroplane, the combination of a frame; a propeller mounting in said frame; a lever on said mounting; a controller lever pivoted on said frame; a cable connecting the forward end of said lever with the rearward end of said controller lever; a cable connecting the rearward end of said lever with the forward end of said controller lever; a stabilizing plane pivotally mounted in said frame; a cable having one end connected with said operating lever, extending to the upper portion of said frame and having its other end secured to the rear edge of said stabilizing plane; and a cable having one end connected to the other end of said controller lever, extending to the lower portion 115 120 125 130

of said frame and having its other end connected to the rear edge of said stabilizing plane, substantially as described.

4. In an aeroplane, the combination of a frame; a propeller pivotally mounted in said frame; a post in said frame; a vertically movable lever pivoted on said post; a second vertical post in said frame; a stabilizing plane pivoted for vertical movement on 10 said last mentioned post; cables operatively connecting said propeller with said controller lever; and cables operatively connecting

said stabilizing plane with said controller lever, one of said last mentioned cables extending above said stabilizing plane and the other of said cables extending under said stabilizing plane, substantially as described. 15

In testimony whereof I have signed my name to this specification in the presence of two subscribing witnesses.

WALTER E. VERCLAIRE.
